[57] CLAIM

The ornamental design for a dog scarf, as shown and described.

DESCRIPTION

FIG. 1 is a front elevational view of the dog scarf showing my new design in an open flat position;

FIG. 2 is a rear elevational view thereof;

FIG. 3 is a front elevational view, shown in use;

FIG. 4 is a rear elevational view thereof;

FIG. 5 is a right side elevational view thereof;

FIG. 6 is a left side elevational view thereof;

FIG. 7 is a top plan view; and,

FIG. 8 is a bottom plan view.

The broken line showing of a dog in FIGS. 3, 4, 5 and 6 is for illustrative purposes only and forms no part of the claimed design.
